UNITED STATES PATENT OFFICE.

ALBERT S. HEINRICH, OF FREEPORT, NEW YORK.

AEROPLANE.

Application filed February 20, 1922. Serial No. 538,081.

To all whom it may concern:

Be it known that I, ALBERT S. HEINRICH, a citizen of the United States, and resident of Freeport, in the county of Nassau and State of New York, have invented certain new and useful Improvements in Aeroplanes, of which the following is a specification.

The invention relates to aeroplanes and more particularly to means for varying the effective span of the aeroplane wings or sustaining members.

In my application Serial No. 517,458, filed November 16, 1921, I have described and claimed a construction in which an increased span of wing area may be provided when desired, the span also being decreased at will, this being accomplished by the provision of sliding auxiliary wing sections which are carried by the main wings and operated by means under the control of the aviator to move the same inwardly or outwardly.

My present invention covers a construction which is in some respects an improvement upon that described in the said application. In the present construction the main wings of the aeroplane are provided with transverse upper and lower beams which are secured at their ends to forward and rear longitudinal beams, the auxiliary wing sections being slidably mounted between the upper and lower transverse beams and with their ends abutting against the forward and rear longitudinal beams. By such a construction it is possible to provide a strong and rigid structure without undesirably increasing the thickness of section and weight of the main wings. In the preferred construction the transverse beams referred to extend partly above and partly below the outer surfaces of the main wings.

An object of the invention is to provide an improved construction of the character referred to. Other objects and advantages of the invention will appear more fully in the following specification and be particularly pointed out in the appended claims.

In order that the invention may be more clearly understood attention is hereby directed to the accompanying drawings forming part of this application and illustrating by way of example one embodiment of the invention. In the drawings—

Fig. 1 represents a top plan view of an

aeroplane equipped with one embodiment of the invention;

Fig. 2 is a vertical section, on an enlarged scale, taken on line 2—2 of Fig. 1;

Fig. 3 is a section taken on line 3—3 of Fig. 2, and

Fig. 4 is a section taken on line 4—4 of Fig. 3.

Referring to the drawings, I have illustrated an aeroplane having a fuselage 1 provided with the cockpit 2 for the aviator and the main wings 3, 3. The machine may, of course, be provided with the usual controlling, steering, propelling and balancing elements which need not be described.

The auxiliary wing sections 4, 4, are slidably mounted on the main wings 3, 3, so as to be extensible beyond the same to increase the span and to be operable to draw the same inwardly, or towards the fuselage.

The main wings are provided with forward and rear beams 5, 5¹, which extend longitudinally of the wings throughout the length thereof. The main wings are also provided with upper and lower transverse beams 6, 6¹, which are firmly secured at their ends to the longitudinal beams 5, 5¹. These transverse beams 6, 6¹ may be termed simple beams since their entire load is transmitted to their end supports 5, 5¹.

The auxiliary wing sections 4 are slidably mounted within the main wings between the upper and lower transverse beams 6, 6¹, and the forward and rear longitudinal beams 5, 5¹. Each auxiliary wing member is provided with longitudinal vertical beams 7, 7, and with suitable transverse struts comprising upper and lower flanges 8, 8, and suitable webs 9 secured to beams 7 and carrying the cap strips. The main wings are provided with upper and lower cover members indicated at 10, 10, and with forward and rear edge web members 11 and 12.

The upper surface of each auxiliary wing section 4 slides in contact with anti-friction bearing means indicated at 13, 13, carried by the upper transverse beams 6 and the lower surface of the auxiliary wing slides in contact with anti-friction means 13¹ carried by the lower transverse beams 6¹, these upper and lower anti-friction bearing members engaging against the upper and lower surfaces of beams 7 in the auxiliary wing section. Anti-friction bearings such as rollers 14, 14, are also provided at the forward

and rear edges of the auxiliary wing members to engage against the forward and rear longitudinal beams 5, 5¹, of the main wings 3.

Means are provided whereby the auxiliary wing sections are positively moved in and out and positively held in adjusted position. As shown in the drawings a shaft 15 extends longitudinally of one main wing and is positively connected to a similar shaft 15¹ extending in alignment therewith longitudinally of the other main wing. Shafts 15 and 15¹ are provided with external screw-threads or worms 16, 16¹, one of the same being right-handed and the other left-handed. A hand wheel 17 adjacent to the operator's seat in the cockpit is connected by suitable means such as shaft 18 and beveled gears 19, 20, to shaft 15 while the screw-threaded portions 16, 16¹ of shafts 15, 15¹ extend through nuts 21 secured to the auxiliary wing sections. With this construction it is obvious that rotation of the hand wheel 17 in one direction or the other will cause the simultaneous movement of the wing sections 4 inwardly or outwardly, these wing sections each necessarily moving through the same distance as the other as they slide outwardly or inwardly.

Each of the beams 7 of an auxiliary wing section is preferably formed of upper and lower tubular members 22 which are joined together by vertical tubular members 23, and by diagonal braces (not shown) which may be secured to flanges 23¹. The upper and lower end portions of vertical members 23 extend partly around tubular members 22, as is indicated at 24. Portions 24 of vertical members 22 are preferably provided with flanges 25 to which the upper and lower strips 26 are secured to extend longitudinally of the wing sections. Ball bearings 13, carried by transverse beams 6, 6¹, engage members 26, these ball bearings being of any suitable type. The webs 9 of the auxiliary wing members 4 are suitably secured to beams 7, as by means of rivets 27, as indicated in Fig. 4. Each transverse beam 6, 6¹, is of suitable truss form and preferably provided with a cover member 28.

The longitudinal forward and rear beams 5, 5¹, of each main wing are preferably constructed in the same manner as the beams 7 to comprise upper and lower horizontal tubular members 29 secured together by vertical tubular members and diagonal braces. The vertical tubular members of these beams preferably have channel members 30 secured thereto against which the end rollers 14 of the auxiliary wing sections will engage.

Each of the upper and lower transverse beams 6, 6¹, of the main wings is provided with vertical flanges 31 adjacent its ends, which are secured to flanged members 32 extending around the vertical tubular portions of beams 5, 5¹. The transverse beams

6, 6¹, are also provided adjacent their ends with horizontal flanges 33, which are secured to suitable flanges on webs 11 and 12 of the main wings which are secured to the beams 5, 5¹.

It will be noted that in the embodiment of the invention illustrated the transverse beams 6, 6¹, each extend partly above and partly below the surface of the main wing indicated at 10, 10. The construction described and illustrated enables the use of a main wing which is comparatively light and small in its vertical dimensions, the upwardly and downwardly directed stresses occasioned by the auxiliary wing members being all taken by the transverse beams 6, 6¹ and transmitted thereby to the forward and rear longitudinal beams 5, 5¹. Endwise thrust of the auxiliary wing member is taken directly by the beams 5, 5¹.

The auxiliary wing sections are shown in extended position in full lines, the positions to which they may be withdrawn within the main wings being indicated in dotted lines. As many of the transverse beams 6, 6¹, as are required may be provided, three of such beams being illustrated as provided for each main wing, extending across the ends thereof and at points located somewhat inwardly from the ends.

It is, of course, obvious that the invention is equally applicable to monoplanes and biplanes. It should be understood that the invention is not limited strictly to the details of construction described but is as broad as is indicated by the accompanying claims.

What I claim is:

1. In an aeroplane, the combination of laterally extending wings, said wings having forward and rear longitudinal beams and transverse beams secured to said longitudinal beams, said wings having interior spaces extending longitudinally thereof and confined between said longitudinal beams, and auxiliary wing sections slidably mounted within said spaces in said wings, adapted to be extended laterally beyond the same, said transverse beams being positioned to extend vertically outside the surface of said wings and arranged to directly receive all upwardly and downwardly directed stresses from said auxiliary sections and transmit the same to said forward and rear longitudinal beams.

2. In an aeroplane, the combination of laterally extending wings, said wings having forward and rear longitudinal beams and transverse simple beams secured to said longitudinal beams, said wings having interior spaces extending longitudinally thereof and confined between said longitudinal beams, and auxiliary wing sections slidably mounted within said spaces in said wings, adapted to be extended laterally beyond the same.

3. In an aeroplane, the combination of a fuselage, wings extending laterally therefrom, said wings having forward and rear beams extending longitudinally thereof and upper and lower transverse beams secured at their ends to said longitudinal beams, said wings having interior spaces extending longitudinally thereof and confined between said longitudinal beams, auxiliary wing sections 5 slidably mounted within said spaces between said upper and lower beams and said forward and rear beams, and adapted to be extended laterally beyond said wings, and means for moving said auxiliary sections towards and away from the fuselage, said transverse beams extending partly above and partly below the outer upper and lower surfaces of said wings.
4. In an aeroplane, the combination of laterally extending wings, said wings having forward and rear longitudinal beams and upper and lower transverse beams secured at their ends to said longitudinal beams, said wings having interior spaces extending longitudinally thereof and confined between said longitudinal beams, and auxiliary wing sections 10 slidably mounted within said spaces between said upper and lower beams with their forward and rear edges abutting against said forward and rear beams, said wing sections being adapted to be extended laterally beyond said wings, and having longitudinal beams extending between their upper and lower surfaces, with anti-friction devices mounted on said transverse beams at points adjacent said auxiliary wing section longitudinal beams.
5. In an aeroplane, the combination of laterally extending wings, said wings having forward and rear longitudinal beams and upper and lower transverse beams secured at their ends to said longitudinal beams, 15 said wings having interior spaces extending longitudinally thereof and confined between said longitudinal beams, and auxiliary wing sections slidably mounted within said spaces between said upper and lower beams with their forward and rear edges abutting against said forward and rear beams, said wing sections being adapted to be extended laterally beyond said wings, and having longitudinal beams extending between their upper and lower surfaces, with anti-friction devices positioned between said transverse beams and said wing section longitudinal beams, said transverse beams being positioned to extend outside the upper and lower surfaces of said wings, and being adapted to directly receive all upwardly and downwardly directed stresses from said wing sections and transmit the same to said wing forward and rear longitudinal beams.
6. In an aeroplane, the combination of laterally extending wings, said wings having forward and rear longitudinal beams and upper and lower transverse beams secured at their ends to said longitudinal beams, and auxiliary wing sections 20 slidably mounted within said spaces between said upper and lower beams with their forward and rear edges abutting against said forward and rear beams, said wing sections being adapted to be extended laterally beyond said wings, said transverse beams being of truss construction, extending above and below the upper and lower surfaces of said wings, and being adapted to directly receive all upwardly and downwardly directed stresses from said wing sections.

Signed at New York, in the county of New York and State of New York, this 11th day of February A. D. 1922.

ALBERT S. HEINRICH.

3. In an aeroplane, the combination of a fuselage, wings extending laterally therefrom, said wings having forward and rear beams extending longitudinally thereof and upper and lower transverse beams secured at their ends to said longitudinal beams, said wings having interior spaces extending longitudinally thereof and confined between said longitudinal beams, auxiliary wing sections slidably mounted within said spaces between said upper and lower beams and said forward and rear beams, and adapted to be extended laterally beyond said wings, and means for moving said auxiliary sections towards and away from the fuselage, said transverse beams extending partly above and partly below the outer upper and lower surfaces of said wings.
4. In an aeroplane, the combination of laterally extending wings, said wings having forward and rear longitudinal beams and upper and lower transverse beams secured at their ends to said longitudinal beams, said wings having interior spaces extending longitudinally thereof and confined between said longitudinal beams, and auxiliary wing sections slidably mounted within said spaces between said upper and lower beams with their forward and rear edges abutting against said forward and rear beams, said wing sections being adapted to be extended laterally beyond said wings, and having longitudinal beams extending between their upper and lower surfaces, with anti-friction devices mounted on said transverse beams at points adjacent said auxiliary wing section longitudinal beams.
5. In an aeroplane, the combination of laterally extending wings, said wings having forward and rear longitudinal beams and upper and lower transverse beams secured at their ends to said longitudinal beams,
- said wings having interior spaces extending longitudinally thereof and confined between said longitudinal beams, and auxiliary wing sections slidably mounted within said spaces between said upper and lower beams with their forward and rear edges abutting against said forward and rear beams, said wing sections being adapted to be extended laterally beyond said wings, and having longitudinal beams extending between their upper and lower surfaces, with anti-friction devices positioned between said transverse beams and said wing section longitudinal beams, said transverse beams being positioned to extend outside the upper and lower surfaces of said wings, and being adapted to directly receive all upwardly and downwardly directed stresses from said wing sections and transmit the same to said wing forward and rear longitudinal beams.
6. In an aeroplane, the combination of laterally extending wings, said wings having forward and rear longitudinal beams and upper and lower transverse beams secured at their ends to said longitudinal beams, and auxiliary wing sections slidably mounted within said spaces between said upper and lower beams with their forward and rear edges abutting against said forward and rear beams, said wing sections being adapted to be extended laterally beyond said wings, said transverse beams being of truss construction, extending above and below the upper and lower surfaces of said wings, and being adapted to directly receive all upwardly and downwardly directed stresses from said wing sections.

ALBERT S. HEINRICH.

Certificate of Correction.

It is hereby certified that in Letters Patent No. 1,558,089, granted October 20, 1925, upon the application of Albert S. Heinrich, of Freeport, New York, for an improvement in "Aeroplanes," an error appears in the printed specification requiring correction as follows: Page 3, line 68, claim 6, after the word "beams" insert the clause *said wings having interior spaces extending longitudinally thereof and confined between said longitudinal beams*; and that the said Letters Patent should be read with this correction therein that the same may conform to the record of the case in the Patent Office.

Signed and sealed this 17th day of November, A. D. 1925.
